RELAY

Ralph A. Geiselman and William H. Cuttino, Wilkinsburg, Pa., assignors to Westinghouse Electric Corporation, East Pittsburgh, Pa., a corporation of Pennsylvania

Application April 27, 1944, Serial No. 533,098

7 Claims. (Cl. 200—98)

1

This invention relates generally to relays and in particular to a regulating relay responsive to reactive kilovolt amperes.

An object of this invention is to provide a regulating relay which is responsive to the reactive kilovolt amperes of a system and which operates positively and definitely upon a predetermined change in the reactive kilovolt amperes of the system.

Another object of this invention is the provision in a reactive kilovolt ampere regulating relay of a restraining force operative to prevent an operation of the relay prior to a predetermined change in the kilovolt amperes and thereafter to permit a positive and definite operation of the relay.

A further object of this invention is the provision of adjustable weights so associated with a relay as to effect a control of the operation of the relay.

Other objects of this invention will become apparent from the following description when taken in conjunction with the accompanying drawing in which:

Fig. 1 is a view in elevation and partly diagrammatic of a relay embodying the features of this invention;

Fig. 2 is a view of a part of the relay taken along the line II—II of Fig. 1;

Fig. 3 is a view in elevation of one of the elements of the relay of Fig. 1;

Fig. 4 is a vector diagram illustrating a certain condition of operation of the relay and

Fig. 5 is another vector diagram illustrating a different condition of operation.

Referring to Fig. 1 of the drawing this invention is illustrated by reference to a reactive kilovolt ampere regulating relay 10 which is connected to a polyphase power circuit represented by the conductors 12, 14 and 16. The relay 10 comprises a contact arm 18 pivotally mounted at an intermediate point on a cross spring pivot 20 to a bracket 22 which is secured to the panel 24. The cross spring pivot 20 is of conventional design being formed of a pair of vertical springs 26 the upper ends of which are secured to an end of the bracket 22 and the lower ends of which are secured to an end of a bracket 28 and a pair of horizontal springs 30 having one end of each secured to the bracket 28 to which the contact arm 18 is secured and the other ends secured to the bracket 22.

The contact arm 18 is of conducting material capable of being magnetically attracted. As illustrated, the contact arm 18 carries a movable

2

contact member 32 to one side of the pivot, the contact member 32 being disposed to be actuated by movement of the contact arm 18 into selective engagement with one or the other of a pair of spaced stationary contact members 34 and 36 which are suitably carried on the panel 24.

In order to actuate the contact arm 18 about its pivot, electromagnets 38 and 40 are provided, the housings 39 and 41 of which are secured to the panel in any suitable manner. The electromagnets 38 and 40 are of similar construction although the direction of winding the energizing windings is controlled to obtain a preferred operation of the electromagnets upon a change in the energization thereof. The electromagnets 38 and 40 comprise the core members 42 and 44, respectively, connected by the stems 46 and 48, respectively, and springs 50 and 52, respectively, to studs 54 and 56, respectively, carried by the contact arm 18 on opposite sides of the pivot.

As illustrated diagrammatically the electromagnets 38 and 40 are provided with voltage windings 58 and 60, respectively, connected through transformer 62 to conductors 12 and 16 and current responsive windings 64—66 and 68—70, respectively, connected in series circuit but preferentially wound and connected through current transformer 72 to conductor 14. Each of the electromagnets 38 and 40 is of the well known type described and claimed in Patent No. 1,565,410 which issued December 15, 1925 to C. A. Boddie, it being noted however that the core member 42 of electromagnet 38 is wound oppositely to the core member 44 of electromagnet 40. Specifically the magnetic fluxes of current responsive windings 64 and 66 are displaced 180 electrical degrees from each other as are also the current responsive windings 68 and 70 while the magnetic fluxes of the voltage responsive windings 58 and 60 are normally 90 electrical degrees from the flux of the two current responsive windings associated respectively therewith so as to be leading with respect to one of the associated current windings and lagging with respect to the other associated current winding. When wound as illustrated the magnetomotive forces of the operating windings may be balanced to provide zero torque on the contact arm 18 at unity power factor in the polyphase power system when the reactive kilovolt amperes are at a minimum. As the reactive kilovolt amperes in the system become lagging the core of electromagnet 38 tends to move downwardly and the core of electromagnet 40 tends to move upwardly

to actuate the contact member 32 into engagement with contact member 34. On the other hand as the reactive kilovolt amperes become leading, the electromagnets 38 and 40 tend to actuate the contact member into engagement with contact member 36.

In order to control the selective engagement of the contact members provision is made for determining the changes in the reactive kilovolt amperes at which the contact arm 18 is actuated about its pivot. For this purpose a pair of weight assemblies 74 and 76 are disposed at the opposite ends of the pivotally mounted contact arm in such a manner as to be free of the contact arm for a neutral position thereof but to be selectively picked up as the contact arm 18 moves about its pivot depending upon the direction of the movement.

By referring to Figs. 2 and 3 the construction and manner of mounting the weight assemblies 74 and 76 is more clearly illustrated with respect to the weight assembly 74 of Fig. 1. As illustrated a clevis 78 is mounted on the panel 24 in any suitable manner. A block 80 is disposed with an end seated against the base of the clevis 78 for sliding movement between the arms thereof as the screw 82, which projects loosely through the arms of the clevis and in threaded engagement through the block, is turned. The block 80 is slotted near its other end for receiving a weight stem 84, a pin 86 being disposed in the end of the block to project across the slot for providing a seat for the stem 84.

As more clearly shown in Fig. 3 the weight stem 84 is provided with a flattened rectangular portion 88 having spaced oblong cutout sections 90 and 92 therein. The cutout section 92 has an open side for fitting over the pin 86 as the stem is mounted in the slot of block 80. The lower portion 94 of the stem 84 is cylindrical terminating with a washer 96 upon which circular or other shaped and slotted weight discs 98 may be seated. When the stem 84 is assembled to seat on the pin 86, the upper end of the rectangular portion 88 fits into a slot in the end of the contact arm 18 in such a manner that the pin 100 projecting therethrough projects through the cutout section 90. By adjusting the position of block 80 in the clevis 78 the stem 84 is so positioned that for a balanced or neutral position of the contact arm 18 the upper and lower edges of cutout section 90 are spaced from the pin 100. In practice the block 80 is so adjusted that the upper edge of cutout section 90 is spaced a slight distance from the pin 100 whereby the stem will be picked up by a small movement of the contact arm 18 in the clockwise direction.

The construction and mounting of the weight assembly 76 at the other end of the contact arm 18 is similar to that of weight assembly 74, the weight stem 102 carrying weight discs 98 being disposed to be picked up by a pin 103 by a counterclockwise movement of the contact arm 18 about its pivot and moved upwardly from the pin 104 in the block 106 which is adjustably mounted in the clevis 108. By adjusting the weight discs 98 on the stems 84 and 102, control of the torque necessary for effecting a movement of the contact arm 18 to effect a selective engagement of the contact members can be readily obtained. As the energizing force is created by the reactive kilovolt amperes in the power system, the change in the reactive kilovolt amperes necessary for effecting a movement of the

contact arm 18 is determined by the weight discs loaded on the stems. This can readily be appreciated by reference to Fig. 4 of the drawing in which a vector showing is made to represent the operation of the relay for given conditions.

Assuming that the system is at unity power factor and has a constant voltage component represented by the line 1-2 the electromagnets 38 and 40 are so balanced that they do not develop a torque on the contact arm 18. By supporting the weight stems 84 and 102 on pins 86 and 104, respectively, the contact arm 18 may be actuated to move about its pivot a limited distance without picking up either of the weight stems 84 and 102 and a limited distance thereafter without effecting an engagement of the movable contact member 32 with either of the stationary contact members 34 or 36.

If a lagging current 0-3 is encountered a torque is built up to effect a counterclockwise movement of the contact arm 18 to a position where the pin 103 picks up the weight stem 102 as the current approaches the value 0-3. As the current increases to the full value 0-3, sufficient torque is developed to lift the weight stem 102 and the contact arm 18 is rotated in a direction towards contact member 34. The value of the in-phase current 0-4 at which such an operation is effected is determined by the number of weight discs 98 carried on the weight stem 102.

Likewise if a leading current 0-5 is encountered a torque is built up to effect a clockwise movement of the contact arm 18 to a position where pin 100 picks up the weight stem 84 as the current approaches the value 0-5. As the current increases to the full value 0-5, sufficient torque is developed to lift the weight stem 84 and the contact arm 18 is rotated in a direction towards contact member 36. The value of the out-of-phase current 0-6 at which such an operation is effected is determined by the number of weight disc 98 carried on the weight stem 84.

In order to provide a positive and accelerated switching operation when sufficient torque is developed by a change in the reactive kilovolt amperes or power factor to actuate the contact arm 18 to pick up either weight stem 84 or 102, a pair of permanent magnets 110 and 112 are disposed adjacent the opposite ends of the contact arm 18. Each of the permanent magnets 110 and 112 is mounted on the panel 24 as shown in Fig. 2 in which the magnet 110 is secured to a block 114 by the screw 116 and washer 118, the block 114 being of non-magnetizable material and being carried on the panel in any suitable manner. The permanent magnets 110 and 112 are so positioned that for a neutral position of the contact arm 18 they have an equalized magnet pull on the arm 18.

When sufficient torque is developed, as by reason of the lagging current 0-3, to lift the weight stem 102 and rotate the contact arm 18 in a counterclockwise direction, the permanent magnet 112 applies an increasing torque to the arm 18 while the torque of permanent magnet 110 decreases, to effect a positive and accelerated movement of the contact member 32 into engagement with the contact member 34. With the weights 98 so adjusted that the contact arm 18 is operated upon the occurrence of an in-phase current 0-4 it is apparent that in any case where the power factor or phase angle of the system is changed in the lagging direction any current that intersects the determining line 3-4

will produce torque sufficient to effect the operation of the contact arm 18 to pick up the weight stem 102 and move the contact member 32 into engagement with contact member 34.

Likewise by adjusting the weights 88 carried by the stem 84 a change in the leading out-of-phase current can be determined at which the contact member 32 is positively actuated into engagement with contact member 36. As represented in Fig. 4 where the power factor or phase angle of the system is changed in the leading direction any current that intersects the determining line 5-6 will produce sufficient torque to actuate the contact member 32 into engagement with contact member 36. Thus the vertical lines 3-4 and 5-6 of the embodiment just described, define the respective limits at which the contact members are actuated into engagement.

In certain applications it is desirable to have the contact members engage within certain limits of leading or lagging current. For this purpose stems 120 and 122 are disposed on the contact arm 18 on opposite sides of and equally spaced from the pivot 20 therefore. The stems 120 and 122 are disposed to receive weight discs or washers 124, illustrated in the embodiment shown as applied only to stem 122, for controlling the quadrature in which the limits are to be established.

With the weight washer 124 disposed on the stem 122 an adjustment is made of the number of discs 98 carried on the stem 102 so that the same torque or current intersecting line 3-4 will actuate the contact member 32 into engagement with contact member 34. However as the washer 124 is then always carried by contact arm 18 it is apparent that the torque necessary to maintain the arm 18 in a neutral position and prevent the weight of the washer 124 from effecting an operation to effect the engagement of contact members 32 and 36 will necessarily be changed. Thus by adding and varying the weight 124 the limiting line 5-6 of Fig. 4 can be changed from the leading quadrature to the lagging quadrature as illustrated in Fig. 5. The addition of washer 124 thus not only changes the quadrature in which contact members 32 and 36 are actuated into engagement but also narrows the limits represented by the distance 4-6 in which the relay operates to effect a controlling switching operation.

If the weight washer 124 is added to stem 120 instead of stem 122 a similar but opposite change will be effected in that the limits for the operation of the relay can be established in the leading quadrature instead of the lagging.

While the relay 10 of this invention has been described without reference to any control system for correcting the leading or lagging reactive kilovolt amperes of the system 12, 14 and 16 it will be understood that it can be applied to many different control systems. One such system in which the relay of this invention is operative upon a predetermined change in the reactive kilovolt amperes of the power system to effect a control operation to correct for such reactive kilovolt amperes is described and claimed in our copending application Serial No. 533,097, filed April 27, 1944 which issued as Patent 2,451,939 on October 19, 1948.

The relay of this invention is sensitive and fast in operation and can readily be adjusted to give a wide variety of operating conditions or predetermined limitations of operation. Further by employing the differential action of the per-

manent magnets, increased sensitivity is obtained as well as a quick make and break of the contact members thereby reducing burning of the contact members.

While this invention has been described with reference to a particular embodiment thereof it is of course not to be limited except in so far as is necessitated by the scope of the appended claims.

We claim as our invention:

1. In a relay, in combination, a pair of spaced stationary contact members, a movable contact member, a contact arm for carrying the movable contact member, a pivot for mounting the contact arm, a pair of electromagnets disposed in spaced relation on opposite sides of the pivot to actuate the contact member, each of the electromagnets having a core member, a voltage responsive winding and a pair of current responsive windings symmetrically placed with respect to the voltage responsive winding on the core member, the pair of current responsive windings being connected in series but being oppositely wound, the windings on the one core member being so proportioned that when oppositely energized to the energization of the corresponding windings on the other core member the core members are simultaneously positionally varied in opposite directions to thereby actuate the contact arm to move the movable contact into selective engagement with the stationary contact members, and a pair of weight means disposed to be selectively carried by the contact arm under predetermined operating conditions to cooperate with the energization of the windings to control the selective engagement of the contact members, said cooperating pair of weight means being disposed out of engagement with the contact arm when the contact arm is in a neutral position with respect to the stationary contact members.

2. In a relay, in combination, a pair of spaced stationary contact members, a movable contact member, a contact arm for carrying the movable contact member, a pivot for mounting the contact arm, a pair of electromagnets disposed in spaced relation on opposite sides of the pivot to actuate the contact member, each of the electromagnets having a core member, a voltage responsive winding and a pair of current responsive windings symmetrically placed with respect to the voltage responsive winding on the core member, the pair of current responsive windings being connected in series but being oppositely wound, the windings on the one core member being so proportioned that when oppositely energized to the energization of the corresponding windings on the other core member the core members are simultaneously positionally varied in opposite directions to thereby actuate the contact arm to move the movable contact into selective engagement with the stationary contact members, a pair of weight means disposed to be selectively carried by the contact arm under predetermined operating conditions to cooperate with the energization of the windings to control the selective engagement of the contact members, said cooperating pair of weight means being disposed out of engagement with the contact arm when the contact arm is in a neutral position with respect to the stationary contact members, and permanent magnet means associated with the contact arm effective when one of said cooperating weight means is carried by the contact arm to

effect a positive accelerated action in the selective engagement of the contact members.

3. In a relay, in combination, a pair of spaced stationary contact members, a movable contact member, a contact arm for carrying the movable contact member, a pivot for mounting the contact arm, a pair of electromagnets disposed in spaced relation on opposite sides of the pivot to actuate the contact member, each of the electromagnets having a core member, a voltage responsive winding and a pair of current responsive windings symmetrically placed with respect to the voltage responsive winding on the core member, the pair of current responsive windings being connected in series but being oppositely wound, the windings on the one core member being so proportioned that when oppositely energized to the energization of the corresponding windings on the other core member the core members are simultaneously positionally varied in opposite directions to thereby actuate the contact arm to move the movable contact into selective engagement with the stationary contact members, and a pair of weights positioned in spaced relation to one another in the path of movement of the pivotally mounted contact arm, the weights being disposed to be selectively carried by the contact arm depending upon the direction of movement thereof about the pivot, the weights cooperating with the energization of the windings to control the selective engagement of the contact members.

4. In a relay, in combination, a pair of spaced stationary contact members, a movable contact member, a contact arm for carrying the movable contact member, a pivot for mounting the contact arm, a pair of electromagnets disposed in spaced relation on opposite sides of the pivot to actuate the contact member, each of the electromagnets having a core member, a voltage responsive winding and a pair of current responsive windings symmetrically placed with respect to the voltage responsive winding on the core member, the pair of current responsive windings being connected in series but being oppositely wound, the windings on the one core member being so proportioned that when oppositely energized to the energization of the corresponding windings on the other core member the core members are simultaneously positionally varied in opposite directions to thereby actuate the contact arm to move the movable contact into selective engagement with the stationary contact members, a pair of weights positioned in spaced relation to one another in the path of movement of the pivotally mounted contact arm, the weights being disposed to be selectively carried by the contact arm depending upon the direction of movement thereof about the pivot, the weights cooperating with the energization of the windings to control the selective engagement of the contact members, and magnetic means associated with the contact arm effective when a weight is carried by the contact arm to effect a positive accelerated action in the selective engagement of the contact members.

5. In a relay, in combination, a pair of spaced stationary contact members, a movable contact member, a contact arm for carrying the movable contact member, a pivot for mounting the contact arm, a pair of electromagnets disposed in spaced relation on opposite sides of the pivot to actuate the contact member, each of the electromagnets having a core member, a voltage responsive winding and a pair of current responsive

windings symmetrically placed with respect to the voltage responsive winding on the core member, the pair of current responsive windings being connected in series but being oppositely wound, the windings on the one core member being so proportioned that when oppositely energized to the energization of the corresponding windings on the other core member the core members are simultaneously positionally varied in opposite directions to thereby actuate the contact arm to move the movable contact into selective engagement with the stationary contact members, a pair of weights positioned in spaced relation to one another in the path of movement of the pivotally mounted contact arm, the weights being disposed to be selectively carried by the contact arm depending upon the direction of movement thereof about the pivot, and another weight disposed to be carried by the contact arm throughout the pivotal movement thereof, the pair of weights and said another weight cooperating with the energization of the windings to control the operating conditions under which the contact arm is actuated to effect the selective engagement of the contact members.

6. In a relay, in combination, a pair of spaced stationary contact members, a movable contact member, a contact arm for carrying the movable contact member, a pivot for mounting the contact arm, a pair of electromagnets disposed in spaced relation on opposite sides of the pivot to actuate the contact member, each of the electromagnets having a core member, a voltage responsive winding and a pair of current responsive windings symmetrically placed with respect to the voltage responsive winding on the core member, the pair of current responsive windings being connected in series but being oppositely wound, the windings on the one core member being so proportioned that when oppositely energized to the energization of the corresponding windings on the other core member the core members are simultaneously positionally varied in opposite directions to thereby actuate the contact arm to move the movable contact into selective engagement with the stationary contact members, a pair of weights positioned in spaced relation to one another in the path of movement of the pivotally mounted contact arm, the weights being disposed to be selectively carried by the contact arm depending upon the direction of movement thereof about the pivot, another weight disposed to be carried by the contact arm throughout the pivotal movement thereof, the pair of weights and said another weight cooperating with the energization of the windings to control the operating conditions under which the contact arm is actuated to effect the selective engagement of the contact members, and magnetic means associated with the contact arm effective when one of the pair of weights is carried by the contact arm to effect a positive accelerated action in the selective engagement of the contact members.

7. In a relay, in combination, a pair of spaced stationary contact members, a movable contact member, a contact arm for carrying the movable contact member, a pivot for mounting the contact arm, a pair of electromagnets disposed in spaced relation on opposite sides of the pivot to actuate the contact member, each of the electromagnets having a core member, a voltage responsive winding and a pair of current responsive windings symmetrically placed with respect

to the voltage responsive winding on the core member, the pair of current responsive windings being connected in series but being oppositely wound, the windings on the one core member being so proportioned that when oppositely energized to the energization of the corresponding windings on the other core member the core members are simultaneously positionally varied in opposite directions to thereby actuate the contact arm to move the movable contact into selective engagement with the stationary contact members, a pair of adjustable weights positioned in spaced relation to one another in the path of movement of the pivotally mounted contact arm, the weights being disposed to be selectively carried by the contact arm depending upon the direction of movement thereof about the pivot, the weights cooperating with the energization of the windings to control the selective engagement of the contact members, and magnetic means associated with the contact arm effective when a weight is

carried by the contact arm to effect a positive accelerated action in the selective engagement of the contact members.
